L. BROWN

DOORLOCK

Filed Nov. 20, 1924

UNITED STATES PATENT OFFICE.

LOUIS BROWN, OF BROOKLYN, NEW YORK.

DOORLOCK.

Application filed November 20, 1924. Serial No. 751,056.

To all whom it may concern:

Be it known that I, LOUIS BROWN, a citizen of the United States, residing at Brooklyn, in the county of Kings and State of New York, have invented certain new and useful Improvements in Doorlocks, of which the following is a specification.

This invention relates to locking devices for dumb waiter door and the like and more particularly to a novel and improved arrangement whereby a plurality of such doors may be simultaneously locked and unlocked.

One of the objects of my invention is to provide an arrangement associated with a plurality of dumb waiter doors whereby a series of catches may be simultaneously manipulated from the basement of a building to lock and unlock the doors and preventing the opening of any one of the doors from the outside of the dumb waiter shaft.

In order to more fully understand and appreciate my invention reference is had to the accompanying drawings, wherein

Figure 1 is a sectional view showing a plurality of dumb waiter doors and the locking mechanism located in the dumb waiter shaft of a building.

Figure 2 is a view of the main lock rod showing the doors in their locked position.

Referring now to the drawings wherein like reference characters designate corresponding parts throughout all the views, 5 designates the wall of a dumb waiter shaft, numeral 6 indicating a portion of the dumb waiter, supported on a cable 7.

A series of guides 8 conveniently located and rigidly secured to the said wall, are adapted to retain a vertical rod 9 extending from the basement to the top of the shaft. The upper end of the rod has a cable 10 attached thereto, said cable passing over a pair of pulley wheels 11 and provided with a suitable weight 12 whereby the rod may be easily manipulated. A lever 13 is pivotally connected as at 14 and attached to the lower end of the rod so that when said lever is depressed, the rod will be moved upwardly through the guides for the purpose now to be described.

50 The dumb waiter doors 15 are each provided with an attaching plate 16 and hook

17. A latch bar 18 formed with a collar 19 is keyed on the rod 9, by a set screw, for instance, the end of the said latch bar co-operating with the hook 17 to lock the dumb waiter door from the inside. Stop collars 19 are also keyed on the said rod 9 to limit the movement of the rod. The lever may be locked by any suitable means such as by a key operated lock, thus assuring a double safety to the doors. It will thus be seen that access to the dumb waiter door catch cannot be had unless from the dumb waiter shaft and all the doors are held in their locked position being in their unlocked position when the rod 9 is raised by means of the lever.

Having shown and described my invention what I now claim as new and desire to secure by Letters Patent is:—

1. A door lock of the class described in combination with a series of dumb waiter doors arranged one above the other for independent swinging movement within a room, an elongated rod positioned within a shaft, guides for said rod, a plurality of laterally extending latch bars adjustably keyed on the said rod, catches located on the doors for cooperation with the latch bars, a shifting lever connected to the lower end of the rod to simultaneously lock and unlock the said latch bars, and a weighted element connected to the upper end of the rod.

2. A door lock of the class described in combination with a series of dumb waiter doors of a shaft, said doors having catches and being arranged one above the other for independent swinging movement from the wall of said shaft into a room, an elongated rod positioned within said shaft, guides on the wall of said shaft for the rod, a plurality of laterally extending latch bars adjustably keyed on the said rod for cooperation with the respective catches, a shifting lever connected to the lower end of the rod and extending through the wall of the shaft, means for locking said lever and a weighted element connected to the upper end of the rod.

In testimony whereof I affix my signature.
LOUIS BROWN.
